UNITED STATES PATENT OFFICE.

HENRY SIEDENTOP, OF JERSEY CITY, NEW JERSEY.

DESIGN FOR FRINGE.

SPECIFICATION forming part of Design No. 17,805, dated October 18, 1887.

Application filed July 8, 1887. Serial No. 243,795. Term of patent 7 years.

To all whom it may concern:

Be it known that I, HENRY SIEDENTOP, of Jersey City, in the county of Hudson, State of New Jersey, have invented a new and original 5 Design for Fringe, of which the following is a specification.

In the accompanying drawing a face view of my new design for fringes is shown.

The leading feature of my design consists in 10 the curled pendants and the curled bows on the heading.

A represents the heading; B, knotted pendants such as are used in fringes.

C represents curled pendants, said curled 15 pendants alternating with groups of knotted pendants B.

D are curled bows above the top edge of the heading, the ends of the said bows being at those points of the heading where the upper

ends of the curled pendants C meet the heading.

Having thus described my design, I claim as new and desire to secure by Letters Patent—

The design for a fringe, substantially as herein shown, the same consisting of a heading, groups of knotted pendants alternating with curled pendants, and curled bows above the top edge of the heading, the ends of said bows meeting the heading at the upper ends of the curled pendants, as set forth. 25

In testimony that I claim the foregoing as my invention I have signed my name in presence of two subscribing witnesses.

HENRY SIEDENTOP.
